UNITED STATES PATENT OFFICE.

HARVEY F. RICE, OF ESPY, PENNSYLVANIA.

THERMOSTATIC CIRCUIT-CONTROLLER.

No. 924,499.

Specification of Letters Patent.

Patented June 8, 1909.

Application filed July 25, 1908. Serial No. 445,327.

To all whom it may concern:

Be it known that I, HARVEY F. RICE, a citizen of the United States, residing at Espy, in the county of Columbia and State of Pennsylvania, have invented new and useful Improvements in Thermostatic Circuit-Controllers, of which the following is a specification.

This invention relates to an alarm apparatus intended to be installed in residences, buildings of various characters, vessels or the like, for protection against fire or other danger conditions, and relates more particularly to an alarm system of that type in which the danger-responsive devices of the rooms, compartments or areas to be protected are arranged singly or in groups in independent normally-closed circuits that contain automatic devices for closing a signal circuit whenever a danger - responsive device is brought into action, the system being so installed as to be proof against tampering with by burglars or other persons with intention to set fire to the building.

25 The invention has for one of its objects to provide an electric fire alarm system with danger-responsive devices such as thermostats adapted to maintain closed circuits when no danger condition exists, and is adapted to open the circuits under danger conditions to bring into service signal devices, the thermostat being of simple and inexpensive construction and so designed as to prevent access to the circuit connections after the thermostat is installed.

30 A further object is the employment of a thermostatically - operated, circuit - opening device adapted to be installed in the room, compartment or area to be protected, and which maintains a closed circuit in which is included a relay that controls a signal circuit, the said device being automatically opened by an abnormal increase in temperature due to fire or other dangerous conditions.

35 With these objects in view and others, as will appear as the description proceeds, the invention comprises the various novel features of construction and arrangement of parts which will be more fully described hereinafter and set forth with particularity in the claims appended hereto.

In the accompanying drawings, which illustrate one embodiment of the invention, Figure 1, is a bottom plan view of one of the thermostatically-operated circuit controllers or openers. Figs. 2 and 3 are, respectively,

a central vertical section and a plan view thereof.

Similar reference characters are employed to designate corresponding parts throughout the several views.

The residence, factory, warehouse, office or other building or vessel equipped with the improved alarm system has at some suitable point a switchboard that contains the visual or audible signals, or both, there being as many signals as there are rooms, compartments or areas to be protected, so that each signal indicates the condition of a predetermined place where a danger responsive device is located.

35 The danger-responsive device, in the present illustration, consists of a thermostatically-operated circuit controller shown in the figures. This device comprises a casing 25 of porcelain or other insulating material that is molded with a chamber 26 which receives the lead-in wires, the casing or insulating base being formed with apertured ears 27 for receiving screws or other fastenings for attaching the device to the ceiling. The walls of the casing are provided with slots or recesses 28 through which the lead-in wires 29, 30, extend, the wires being thoroughly concealed and protected so that the wires cannot be cut by any one intending to set fire to the building. The bottom of the chamber 26 is formed with recesses 31 into which are set nuts 32 of the screw bolts 33 that secure the metal expansible disk or diaphragm 34 to the insulating base. The bottom of the base is provided with a depending rim 35 within which is confined the disk 34, the latter having its central portion dished outwardly so as to expand further outwardly when subjected to heat. The base 25 is formed with a central opening 36 for receiving the relatively-stationary contact device 37 which has its lower end pointed and disposed normally in contact with the center of the disk 34.

40 The contact device, as shown in Fig. 3, consists of a screw 38 threaded in a bushing 39 disposed in the opening 36 of the base 25 and held in place by a flange 40 and nut 41 set into recesses 42, 43 on the bottom sides of the base. One lead-in wire is clamped to this contact device by the nut 41, while the other lead-in wire is electrically connected with the disk 34 by being connected with one of the bolts 33. The screw 38 is adjusted to normally bear on the disk 34 to complete

the circuit, and, by varying the adjustment of the screw, the degree of temperature at which the circuit will be opened can be regulated. For instance, when it is desired to set the device to open at relatively low temperature, the set of the screw will be such that it will bear against the disk 34 with a comparatively light pressure, whereas when the active temperature is to be higher, the 10 screw will be adjusted to exert a greater pressure on the disk so that more expansion will be required for the disk to move away the contact on screw 38.

A thermostatically-operated circuit-controlling device of this design is simple, durable, tamper-proof, readily adjusted and reliable. It is impossible to put this system 15 out of commission without turning in an alarm, either by the breaking or burning off 20 of the wire, the breakage of the porcelain base, or the removal of the disk.

From the foregoing description, taken in connection with the accompanying drawings, the advantages of the construction and of the 25 method of operation will be readily apparent to those skilled in the art to which the invention appertains, and while I have described the principle of operation of the invention, together with the apparatus which I now 30 consider to be the best embodiment thereof, I desire to have it understood that the apparatus shown is merely illustrative, and that such changes may be made when desired as are within the scope of the 35 pended claims.

Having thus described the invention, what I claim is:—

1. The combination of a chambered insulating base having slots in the wall thereof

and having spaced apertures in the bottom 30 adjacent the said wall and also having a central opening, a metal disk having apertures registering with those in the base and formed with its central portion dished outwardly away from the base, bolts passing 45 through the apertures of the base and disk, a contact point in the said opening and arranged normally in contact with the inner surface of the disk, a bushing fitted in the opening and in which the contact point is 50 threaded for adjustment therein, means for connecting a conductor with the said bushing, and conductors extending into the base through the slots thereof and connected one with one of the said bolts and the other with 55 the said bushing.

2. In a thermostatically-actuated circuit controller, the combination of an insulating base having a chamber in its top and apertured ears for receiving fastening devices, 60 the bottom of the chamber having an opening, a disk secured to the under side of the base and disposed over the opening, an internally-threaded bushing secured in the opening and forming a binding post, means for securing 65 a wire to the bushing, means within the said chamber for electrically connecting a wire with the disk, the wires extending into the chamber through slots, and a contact element adjustably mounted in the bushing and 70 normally bearing on the disk.

In testimony whereof I affix my signature in presence of two witnesses.

HARVEY F. RICE.
